ATTACHING MECHANISM FOR SUCTION CLEANER NOZZLES AND THE LIKE

Filed July 16, 1928

UNITED STATES PATENT OFFICE

CHARLES B. LAWRENCE, OF CLEVELAND, OHIO, ASSIGNOR TO THE P. A. GEIER COMPANY, OF CLEVELAND, OHIO, A CORPORATION OF OHIO

ATTACHING MECHANISM FOR SUCTION CLEANER NOZZLES AND THE LIKE

Application filed July 16, 1928. Serial No. 292,994.

My invention relates to improvements in attaching mechanism for suction cleaner nozzles and the like, and has for its object the provision of means for securely attaching and detaching two members in co-operative relation, and, more particularly, means for readily functioning to secure a removable nozzle upon its suction cleaner casing, which act in two planes substantially at right angles to each other, which means shall be simple and cheap to construct, and will not deteriorate after normal use and wear of the parts.

Several prior structures of this class have appeared in the art for detachably securing suction cleaner nozzles in position, and although proving efficient upon initial use, the wear of the parts results in an imperfect fitting, and even looseness and chattering of the nozzle as the suction cleaner is rapidly moved back and forth while in use. Brush attachments frequently are applied to nozzles of this type, hence there are exerted both a downward pressure, together with resistance to the back and forth movement of the brush, or even resistance to the action of the floor covering upon the nozzle mouth. Accordingly, it is highly desirable securely to attach a removable nozzle against movement independent of the suction cleaner in vertical as well as in horizontal planes.

These features have been borne in mind in completing the instant improvements, which may best be explained in connection with the accompanying drawings, wherein:

Figure 1 is a view of a suction cleaner, shown in side elevation, equipped with my improvements,

Fig. 2 is a front view of the suction cleaner casing and detachable nozzle, shown upon a larger scale,

Fig. 3 is a similar fragmentary view with the nozzle removed,

Fig. 4 is a fragmentary side view of the upper portion of the nozzle,

Fig. 5 is a similar front view thereof, partially sectioned, and

Figs. 6 and 7 are rear and side views of the double-locking cam and lever.

Throughout the several figures of the draw-

ings I have employed the same character of reference to indicate similar parts.

In Figure 1 the fan casing *a* is shown with front and rear supporting wheels *a'* and a rearward motor casing *a''*. The handle *b* (shown broken away) is pivoted at *b'* adjacent to the adjusting arc *b''* for holding said handle, when desired, at any particular angle, by means of a transverse bolt *c* and clamping nut *c'*.

At the front of casing *a*, Fig. 3, there are provided a pivoted cam lever *d* and opposing screws *e*, *e*, positioned at 120° about the opening into the fan casing whereon a slightly elevated seat *a³* is designed to receive the rear flange *f'* of the suction cleaner nozzle *f*. This flange is adaptably notched at 120° respectively to accommodate the screws *e*, *e*, as at *f'', f''*, as well as the conforming circular portion of the cam lever, as at *f³*, for the purposes hereinafter explained.

The details of the cam lever, having the double function previously referred to, may best be understood by making reference to Figs. 6 and 7. The lever *d* has a pivotal bore *d'*, a mutilated circular hub *d''*, and an angular cam face *d³*. When the nozzle is positioned before the fan case opening, supported by the spaced screws *e*, *e*, and steadied by the pin *e'*, the cam lever may be actuated to bring the circular hub *d''* into register with the semi-circular slot *f³*, as the lever is turned in a clockwise direction, while simultaneously engaging the inclined cam face *d³* with the flange *f'* in its upper portion adjacent to the slot *f³*. This serves securely to hold the nozzle firmly in position at the front of the fan casing, and prevents its relative movement and possible chattering during the use of the suction cleaner. It will be seen that the screws *e*, *e*, are adjusted to accommodate with a close fit beneath their heads and hold the lower portion of the flange *f'* in position, while the hub *d''* of lever *d* depresses the flange vertically against the screws, and the inclined face *d³* clamps the upper portion of the flange tightly against its seat *a³*. This also compensates for wear.

Reversely turning the cam lever *d* to its upper position shown in Fig. 3, immediately

serves to release the flange f' adjacent to the lower mutilated area of the lever, whereupon the nozzle may be slightly elevated and tilted to free it from the stops or screws e, e , as well as the normally opposing portions of the locking lever. Thus the nozzle may be removed and replaced by another tool, or the suction cleaner, freed therefrom, is better adapted for storage, as in a contracted broom closet.

10 It will be understood, particularly referring to Figs. 2 and 6, that the mutilated portion of the hub d'' will serve, if necessary, to afford a camming action and force the flange vertically against its opposing abutments, 15 after which the circular portion of d'' enters the conforming circular faced slot f^3 , thereby serving to hold the flange and nozzle against vertical movement with respect to the fan casing. The cam face d^3 simultaneously clamps the flange, acting substantially in a horizontal plane against the seat a^3 , and avoids substantial loss of suction between the fan casing a and nozzle f . By employing the cam lever herein disclosed, or an equivalent rotatable 20 locking member, the important double function of accurately positioning and securely locking two separable coacting members is attained, by means acting in planes approximately at right angles to each other.

30 Having now described the embodiment of my invention and its utility in securely attaching and detaching associated members, I claim as new, and desire to secure by Letters Patent, the following:

35 Attaching means of the class described, comprising an attaching flange peripherally recessed approximately at 120° , the edge of one of said recesses forming a cam seat, a co-acting member to which the flange is adapted to be attached, and attaching means thereon, 40 including stops registering with two of said recesses, and a rotatable attaching member having cam faces positioned to act upon the recessed edge and the face of the flange approximately at right angles, substantially as set forth.

In testimony whereof I do now affix my signature,

CHARLES B. LAWRENCE. [L. S.]
